(57) **CLAIM**

The ornamental design for a component of a minimal-invasive disc system, as shown and described.

DESCRIPTION

FIG. 1 is a front perspective view of a component of a minimal-invasive disc system according to my new design;

FIG. 2 is a rear view of the component of FIG. 1;

FIG. 3 is a side view of the component of FIG. 1; and,

FIG. 4 is a front view of an attachment for the component of FIG. 1.

The broken line included depicts environment and is not part of the claimed design.
